LOOM FOR MIXING FILLING

William H. Baker, Montreal, Quebec, Canada

Application January 18, 1933, Serial No. 652,843

8 Claims. (Cl. 139—243)

In weaving the finest grades of woolen fabrics, such as worsted suitings, it is necessary to avoid the insertion of two successive picks of filling from the same bobbin, because uncontrollable slight variations in the nature of the filling yarn wound onto two different bobbins from a common source of supply produce a perceptible difference in their appearance in the fabric. So important is it to mix the picks from different bobbins that it has become the established practice in making these highest grade fabrics to employ not less than three shuttles, each containing filling from the same source and as closely alike as possible, working each shuttle for a single pick only and then succeeding it with the other two or more in a constant series or rotation, so that the successive picks from any one bobbin are separated by two or more picks each of which comes from a different bobbin.

The successful working of the filling in this manner compels the use of change-box looms equipped with shifting shuttle-boxes having two or more cells at each end of the lay, with the attendant box-operating and box-calling mechanism, and these looms are ordinarily not regarded as good investments, because they could not hitherto successfully be arranged to replenish their filling supplies automatically, with the result that the manufacture of these fabrics when exhibiting the highest degree of perfection has been costly and little indulged in.

But I have devised a way in which these change-box looms can be rendered completely automatic in the replenishment of their filling supplies, while being worked in the above manner to insert successively a single pick of filling from each of three or more separate bobbins. Recognizing and utilizing the fact that in this method of weaving at least one cell at one end of the lay is always empty when the lay beats up, I accomplish the necessary changing of the bobbin just prior to its complete exhaustion, by receiving its shuttle in one cell of one shifting shuttle-box, forcing a fresh bobbin into the shuttle by the usual methods and mechanism, and expelling the old bobbin through the adjacent cell or cells in this shuttle-box while the latter are empty. Or I may carry the fresh bobbin through the empty cell first. The shuttle-box is locked against shifting, enabling proper seating of the new bobbin in the spring jaws of the shuttle. I employ a single feeler to detect approaching exhaustion of filling in all the shuttles, bringing the latter in succession into contact with the feeler for this purpose. When substantial ex-

haustion is detected in any shuttle, I set the replenishing mechanism to function on the next arrival of this detected shuttle in the replenishing cell of the shifting shuttle-box at the replenishing end, and not until such arrival. Other features and advantages of the invention are as will be made plain hereinafter.

An illustrative embodiment of the invention is set forth in the accompanying drawings, in which:—

Fig. 1 is a front elevation of a 2x2 drop-box loom, with the improvements of the invention applied thereto.

Figs. 2 and 3 are plan and right-hand end views of the same.

Fig. 4 is an enlarged side elevation, partly in section on line 4—4 of Fig. 1, showing the parts and arrangements employed at the replenishing end to effect automatic replenishment, the parts being in their normal inoperative position.

Fig. 5 is a plan view of the shifting shuttle-box in which replenishment is effected, showing the shape of the box and the means for withdrawing the lower binder and locking the boxes against shift.

Fig. 6 is a front elevation of certain of the parts of Fig. 5.

Fig. 7 is a view in vertical section on line 7—7 of Fig. 5.

Fig. 8 is an enlarged detailed view in plan of 30 the box-locking and binder-relieving features.

Fig. 9 is an enlarged elevation taken obliquely from the front, showing certain of the members of Fig. 8.

Fig. 10 is a view of the transerrer-dog on its supporting arm, also showing the actuator provided to work the box-lock and binder-remover.

Fig. 11 is a detail of this actuator.

Fig. 12 is a schematic showing of the picking order of the several shuttles, giving the sequence 40 of the various operations involved in the invention, and being carried through three cycles, one for each shuttle.

Fig. 13 is a plan view, and Fig. 14 a front elevation, of certain parts at the left-hand end of the breast beam and lay, showing the feeler and its transmitting devices.

Fig. 15 is a plan view of a shuttle in its replenishing box directly after replenishment, showing 50 the way of handling the new weft end.

Fig. 16 shows the normal inoperative relation between the feeler-governed latch and its actuator.

Fig. 17 shows the operating engagement effected between the latch and actuator of Fig. 16 55

by the feeler on detection of substantial weft-exhaustion.

Fig. 18 is a detail side elevation showing the feed-pawl arrangement for the rotor of the 5 magazine.

Fig. 19 is a rear view of the parts of Fig. 18.

Fig. 20 is a more or less diagrammatic showing, in side elevation, of an alternative method of replenishing.

10 Fig. 21 is a rear view of certain of the parts of Fig. 14.

15 The invention principles, though equally applicable to change box looms employing a greater or less number of shuttles, is herein illustrated 20 for simplicity in a drop-box loom employing three shuttles and having two cells in each shifting shuttle-box at each end of the lay. The loom itself, apart from the special instrumentalities provided and employed for the practice of the 25 invention, is or may be all as usual or as desired in the way of a 2x2 drop-box loom.

30 In accordance with the invention in the illustrated preferred form, a filling-feeler or depletion-indicator 1 is mounted on a suitable stand 3 fixed on the lay end 4 so that the filling-engaging member 5 will be brought into feeling contact with the bobbin 71 occupying the top cell 7 of the left-hand change-box when the box is lifted to bring the lower cell 9 in picking relation with 35 the shuttle-race 11. The practice of the invention is in no way limited to any specific nature of feeler employed, a feeler of the side-slipping type being shown herein for purpose of illustration only.

35 The side-slipping filling-engaging member 5 has a striker 13 projecting forwardly therefrom which when the member 5 slips sidewise in familiar manner upon engagement with a substantially denuded bobbin is brought by the forward 40 beat of the lay into the dotted-line position of Figs. 13 and 14, and into contact with a finger 15 of a bell-crank pivotally mounted on a stand 17 positioned outwardly from the left-hand end of the breast-beam 19 by means of a bracket 21.

45 A transmitter 23, pivoted to the other arm 16 of this bell-crank, has its inward end bent obliquely upward and then levelled off again into parallel with its main extent, this level extremity 25 supporting the usual latch 27 pivoted to the upper 50 end of the arm 29 fixed on the controller rock-shaft 31 which when rocked sets the replenishing devices in position for actuation through the forward beat of the lay, as usual. The inward push given to the transmitter 23 when the feeler slips 55 sidewise serves to propel the lower bend up an inclined shoulder 24 at the rear surface of the rigid extension 22 of a small stand 26 fixed on the breast-beam to raise the notched rearward end of the latch 27 from its normal depressed position 60 of Fig. 16 into the path of the actuator 33, as shown in Fig. 17, whereby the forward motion of the actuator may rock the controller rockshaft 31 in known manner to call the filling change.

65 The actuator, pivoted at 35, Fig. 3, on the loom side, is in accordance with the invention actuated at one-half its ordinary speed, through engagement of its rearwardly extending arm 37 with a cam 39 on a countershaft 41 which is rotated at exactly one-half the speed of the regular cam-shaft of the loom, one-fourth the speed of the crankshaft, through two to one reducing gears 43, 45, on the camshaft and countershaft respectively, and engaging each other.

70 Because the striker 13 strikes and actuates the 75 finger 15 and recedes rearward again out of con-

tact with such finger before the latch 27 can be engaged by the actuator 33, means is provided to hold the latch 27 in the path of the actuator comprising a yielding plate 28 between which and the adjacent face of the upward extension 22 the 5 bent-under portion of the transmitter 23 is frictionally gripped. The movable plate 28 has a projection 30 at its bottom which is stepped loosely in an aperture 32 in the stand 26, while a screw 34 passing loosely through a hole in the 10 upper extremity of the plate 28 adjustably compresses an expanding spring 36 around its shank against the rear side of plate 28, to create a binding or pinching force on the portion of transmitter 23 which is confined and guided between 15 extension 22 and plate 28 insufficient to resist travel of the transmitter up the incline 24 to put the latch 27 in the path of the actuator 33, but holding the transmitter and latch in uplifted position until engagement between the latch and actuator shall have occurred on the latter's next excursion forward. Thus is provided the means for holding the replenishing devices and the controls therefor in readiness to operate, irrespective of the position, relation, or movements of the 20 feeler subsequent to its performance of its function.

To reset the linkage which transmits the impulse from the feeler to the latch 27, to reset the parts automatically for subsequent operations on another filling-supply, the latch 27 is equipped with an integral cam-surface 34 standing normally rearward of the horizontal extremity 25 of transmitter 23 supporting the latch. As the latch is driven forward following engagement 35 with actuator 33, this surface cams the end 25 downward from its position in Fig. 16 to the dotted-line position in Fig. 17, working the linkage reversely to the movement imparted by striker 13, and forcing the transmitter down 40 slope 24, all the parts having thus been restored to their normal waiting position indicated in full lines in Fig. 13.

The devices for effecting the actual insertion 45 of the fresh bobbin in the shuttle which contains the bobbin found by the feeler to be substantially depleted are or may be as usual, with the exception of the modifications which form a part of the present invention. In the illustrative embodiment, these replenishing devices are as 50 shown and described in U. S. Patent No. 1,259,768, J. Northrop, March 19, 1918, except as stated to be otherwise. The controller rockshaft 31, Fig. 4, has fixed thereon an arm 47 which extends rearward under the breast beam and terminates in 55 a sleeve in which slides a vertical rod 49, an expanding spring 51 surrounding the rod and being confined between the top surface of the sleeve on arm 47 and a collar 53 fixed on the rod, so as to transmit yieldingly to the rod 49 an upward push incident to rotation of the rockshaft 31 and corresponding upward movement of the rear end of arm 47 which results from the aforesaid engagement of the latch 27 by actuator 33. A collar 55 on the rod below the arm 47 ensures 60 retraction of the rod downward again when the arm 47 recoils downward under the pull of its spring 57. The upper end of rod 49 is pivotally combined with a pin on the angular extension 63 of the shuttle-feeler 65, rearward of the latter's pivot 67. As usual, if the shuttle-feeler can assume its intended position across the shuttle-race when the lay approaches and arrives at front center, the rotation thus permitted the shuttle-feeler causes the latch-lifting arm 62, moving in 65

unison therewith, to tip up the latch or trans-ferrer-dog 69 into position to be struck by a bunter surface on the lay, thereby to derive motion forcing the trans-ferrer 71 downward to drive 5 a new bobbin 73 from the rotor 14 of the magazine into the shuttle 75 occupying the uppermost cell while the latter is raised into its inoperative or idle position above the level of the shuttle-race, and the lower cell is in operative 10 alignment with the shuttle-race.

Improved means is provided for positioning the next bobbin which is to be transferred from the rotary magazine, so that it will unfailingly be accurately presented to the blow of the trans-ferrer and to the jaws of the shuttle below it. 15 Such means give the rotor 74 of the magazine a rotational bias tending to rotate it clockwise in the drawings and tending to operate from the moment the change is called on rocking of the controller-rockshaft and until after the trans-ferrer has acted, which bias brings and holds the first available bobbin in the rotor firmly against the bobbin-stop 76, so that no backlash or play back and forth can arise to impair the 20 aim of the trans-ferrer and cause improper transfer. Thus, the feed-pawl 78 is rendered independent of the trans-ferrer, being pivoted at 89 on one arm of a carrier-lever 82 pivoted on a stud 84 fixed in the magazine stand and on which stud the holding-pawl 98 also is pivoted. 25 The other arm of lever 82 is pivoted to a link 88 whose front end passes freely through a hole in the latch-lifting arm 62 of the shuttle-feeler. A collar 88 is fixed on the link beyond the arm 62 and an expanding spiral spring 90 is confined 30 around the link between the arm 62 and such other arm of lever 82.

An expanding spiral spring 92 has its upper end in engagement with a point on a horizontal forward extension or tail 94 of the pawl 78 and its lower end engaging with an opposing portion 96 of the magazine stand to hold the pawl against the ratchet. Thus on the rocking of the controller-rockshaft 31 the rearward movement of the shuttle-feeler 65 compresses spring 90, acting to lift the feed-pawl bodily upward, thus moving the rotor clockwise until the head of the first bobbin 73 is definitely positioned against the stop 76, maintaining it there until it is struck by the trans-ferrer; thereafter, the energy still stored in the spring 90 moves feed-pawl 78 farther upward and advances the rotor after the trans-ferrer has again risen, thus bringing the next bobbin into 45 position against the stop and beneath the trans-ferrer. The holding pawl 98 maintains the parts in this position while the feed-pawl 78 recedes to its normal position, and until another bobbin is to be inserted in a shuttle. The strength of 50 spring 90 is sufficient to impart enough impetus to the rotor to carry it two or more bobbin-spaces past the bobbin-stop in case one or two bobbins are lacking at this point in the rotor; but it is inferior to the strength of spring 51 which acts as the give-away when the shuttle-feeler strikes an improperly boxed shuttle.

At the beat up of the lay at which the transfer of the new filling supply into the shuttle occurs, the working cell of the shuttle-box at the re-plenishing end of the lay is empty, this being attained by appropriate setting of the cam 39 on the countershaft 41. Thus the expelled exhausted bobbin 71 can descend through the lower cell, the bottoms of the top and bottom cells being appropriately cut away as indicated at 79

in Figs. 4, 5 and 7, for the necessary length and width to permit the old bobbin to fall through and thus to be discarded from the lay. Correspondingly, the top wall of the top cell is cut back and away as indicated at 81, Figs. 5 and 7, 5 to admit the new bobbin 73.

Means are provided to withdraw the binder 85 from the lower cell, at the moment transfer occurs, to leave an unobstructed passage ensuring certain escape of the old bobbin. Such means 10 comprise a lever 87 pivoted by means of a pin 89 on the underside of a fin 91 extending forward as an integral part of the shifting shuttle-box on a level with and forming a continuation of the bottom of the top cell. This fin, as an additional 15 feature of the invention, I employ instead of the usual bunter on the lay to strike and actuate the trans-ferrer-latch 69 to provide the impetus for the transfer. The lever 87, as shown best in Figs. 6, 7 and 8, has at its left-hand end a 20 downwardly extending finger 93 standing behind the free end of the binder 85, so that rearward pressure on the right-hand end of this lever will pull the binder forward out of the lower cell, 25 from its full-line position in Fig. 8 to that indicated in dotted lines.

To work the lever 87, an actuator 95, Figs. 4, 10 and 11, is pivoted by means of its integral stud 97 on the lower end of an arm 99 fixed against any rotation whatever on the trans-ferrer-stud 100. Though this actuator 95 normally gravitates down and hangs idly as shown in Fig. 4, an arm 102 is fixed on stud 104 to which is fixed the trans-ferrer-dog or latch 69, the stud rotating freely in the lower end of arm 72 of the trans-ferrer so that when the dog 69 is lifted the arm 102 will swing rearwardly and a pin 106 in its free end will slide along a cam surface 108 on the under side of the actuator 95 and tip up the actuator so that it will encounter the free end of binder-relieving lever 87 and push such free end rearwardly until flush with the oblique edge of the fin 91. The push given to the lever by the actuator 95 is made yielding by presenting to the advancing free end of the lever a plunger 110, backed up by a stiff expanding spring 112 confined in a bore 114 in the actuator by a plug 115 secured by cotter-pin 116. Suitable extensions 118 rearwardly of the plunger ensure certainty of its engagement 50 with the lever, aided by a stop 117 engaging the side of arm 99 to prevent overthrow.

To lock the shifting shuttle-box at the proper level to ensure complete and accurate seating of the new bobbin by the trans-ferrer with its rings 55 properly gripped by the spring jaws in the shuttle, a pin 120 is suitably fixed as by nuts 122 in a hole at the front end of a forward extension 124, fixed on the lay end at 126, this locking pin extending through a hole 128 in the fin 91 within the path of swing of the lever 87. The side of this locking-pin is slotted at 130, Figs. 8 and 9, so that this lever, when swung by engagement with its actuator 95 into the dotted-line position of Fig. 8 to withdraw the lower binder, will enter 60 this slot and lock this shifting shuttle-box against movement downward under the blow transmitted to it by the trans-ferrer in driving the fresh bobbin into the shuttle. This locking is a vital 65 essential to successful transfer into a shifting shuttle-box, for in the absence of means for locking the box, the give-way mounting of the box necessary to provide for trapped shuttles would tend to let go wholly or partly at the instant of transfer, resulting in improper seating of 75

the new bobbin through downward yielding of the shuttle-box and other obvious complications. The sustaining effort of pin 120 is preferably applied as close as possible to the point of application of the blow incident to transfer, namely at the point in the drop-box length where the butts of the old and new bobbins come together, to prevent twisting of the drop-box in its guides. To prevent the lever 87 accidentally engaging the notch 130, a contracting spring 133, anchored to the fin at 134, normally holds the lever away from the pin 120.

Because it is essential to complete the locking of the boxes by lever 87 completely before the bobbin transfer commences, the actuator 95 is set so that its plunger 110 will have struck and moved lever 87 into the dotted-line or completely locked position of Fig. 8 before the striker edge 91 of the fin engages the transferrer-dog 69. See Fig. 5. The spring 114, which is superior in strength and leverage to spring 133, provides for the necessary actuation of the lever 87 by plunger 110 just referred to and still to permit the final increment of forward travel 25 of the lay which actuates the transferrer. The offset relation of the exposed portion of lever 87 with respect to the portion of the fin 91 which engages the transferrer-dog, ensures that this lever will not be broken off in case the shuttle-feeler 65 revokes the transfer and depresses the transferrer-dog.

Since in the preferred embodiment of my invention shown in Figs. 1-12, the shuttle to be replenished is not on the level of the shuttle-race, but is raised at least one cell above such level, the shuttle-feeler 65 has to be arranged in new manner. For the same reason, the whole transferrer mechanism, as will be obvious, is likewise raised the height of at least one cell above 35 the shuttle-race. Hence, to determine whether the shuttle is in proper position for replenishing, the shuttle-feeler swings through a slot 136, Fig. 6, cut in the front wall of the shifting shuttle-box, extending partway down from the level of the partition between the top and bottom cells, which partition is correspondingly cut away as indicated at 138, Fig. 5, and feels for the tip of the shuttle in known manner. As usual, the shuttle-feeler carries the old weft-end parter 40 and holder 66, which as seen operates at a height 50 one cell above the shuttle-race.

Because of the new problems introduced by replenishing into a shuttle elevated above the shuttle-race, which involves the corresponding elevation of the replenishing instrumentalities, magazine, etc., and also because of the necessary order of working the boxes, a new system of controlling the old and the incoming weft ends has had to be devised. After the fresh bobbin 55 has been inserted at front center into the uplifted top cell of the right-hand box, the lay has to make an excursion rearward and again forward before the shuttle goes into action. If the weft-end should be left to its own devices, it 60 would be broken on the first rearward beat of the lay, because the yarn would not be drawn off from the new bobbin from the end thereof but would be pulled in a varying generally radial direction. For this reason, a shuttle-threader 144, 65 Figs. 5 and 15, is provided at the outward end of the top cell beyond the outermost position of the slit-threader of the shuttle and on the top surface of such cell, substantially in line with the axis 70 of the bobbin in the shuttle of such cell. Normally, this pin passes just below the weft-end of

the lowermost bobbin standing in the rotor in readiness for replenishment; but when this lowermost bobbin is forced into the shuttle, the changed angle of its filling end brings the latter into position to be intercepted by the pin on the next rearward stroke of the lay. Bending around this pin, the weft is always maintained in line with the bobbin axis, and can draw freely over the end of the bobbin and around this pin to provide the necessary length for the back stroke of the lay. Further, this drawing-off action effects the threading of the shuttle during this same back stroke of the lay and wholly before this shuttle is picked, the top surface of the top cell of the right-hand shuttle-box being cut away as indicated at 148, Figs. 5 and 15, to provide for the necessary descent of the new weft-end into the thread passage of the usual automatic slit-threader occupying the proximate end of the shuttle as shown in Fig. 15.

When the newly replenished shuttle is lowered into working position by the shift of the change-box, this second change in the angle of lead of the new weft-end lifts it off from the shuttle-threading pin 144. This is necessary, in order 25 that on the ensuing pick the weft shall be laid far enough forward of the reed to fall in the path of the filling-fork. As a further protection, the weft-end is prevented from slipping rearward around the under surface of the thread-support 30 150 of the magazine to a point where it likewise could escape the filling-fork, by a weft-end 35 detent 152, Figs. 3 and 15, mounted on a part of the loom arch or other fixed part, which presents a U-shaped trap to intercept each weft-end in turn as its bobbin arrives in replenishing position in the magazine, engaging the weft-end between the thread-support 150 and the end of the bobbin at a point close to the thread-support. Engaged in this U-shaped trap, the new weft-end 40 is prevented from shifting around the rim of the thread-support 150, and is given the proper starting point for its angular extent across the loom so as to be laid properly in the path of the weft-fork. The rearward extent of the detent adjacent the U-shaped trap serves as a guide-surface 45 to lead each weft-end in turn into the trap.

To permit escape of the old weft-end extending from the selvage to the weft-parter 66 and held by the latter after parting, so as to prevent breakage of this length of filling by the receding lay, the usual mouth-piece of the upper cell, against which the binder thereof normally takes bearing, is dispensed with, and the box is wholly open at its front side, from the binder-guide 140 inward. 55 But to prevent this old weft-end escaping forwardly out of this end of the top cell so as to avoid the weft-parter, after this cell has been lifted and during the rearward movement of the lay incident to picking out the lower shuttle from beneath this cell preparatory to the replenishing action, a thread-catcher 154 projects up as an extension of the front wall of the lower box above the level of the floor of the top box, so as to present a thread-engaging rearward surface which keeps the weft-end of the spent bobbin within the top cell in position to be seized and parted by the weft-parter 66. In doing this, the weft-parter lifts it sufficiently out of the box as the lay recedes after parting, this action being 60 facilitated by bevelling the outward end of this part of the thread-catcher as shown in Fig. 6.

To prevent either slack forming in the old weft-end between the selvage and the weft-parter 66, or the creation of enough tension to 75

pull the old end out of the weft-parter, either of which events would otherwise cause this end to fail to be turned off by the selvage-grimmer, the shuttle-feeler is mounted on its pivot 67 to swing in a vertical plane fore and aft the loom, with no movement along the axis of such pivot, thus attaining the substantially equidistant position of the weft-parter at both extremes of the shuttle-feeler's stroke needed to guide the weft-end into the selvage-trimmer. This results from parting the weft at the elevated position of the inactive cell.

It is to be noted that the whole top surface of the top cell has been cut back as indicated at 81 to form a narrow shuttle-guide only a small fraction of an inch in width. Thus the new weft-end, still held at one end through attachment to the magazine, swings freely upward and forward out of the top cell as the newly replenished shuttle is picked. To prevent this weft-end from being caught by the notch in locking-pin 120, which now stands about at the level of the top of the upper binder-guide, a thread-deflector 156 is provided in connection with the top 25 of the binder-guide 140 for the top cell, which steers the trailing new weft-end clear of this pin and other parts on which it might become entangled in its egress from the top cell. To prevent its reentry or possible fouling on the parts 30 of the lay and shifting shuttle-boxes on subsequent forward beats of the lay, a shield 158, Fig. 7, is mounted on the usual striker 160 provided in usual manner on the lay end to close the weft-parter. This shield is of suitable shape to prevent the filling, once it has escaped, from returning on subsequent beats of the lay, to become fouled on the end of the binder, binder-guide, locking-pin, or other parts. This shield may be of slender circular cross-section, and as shown 35 in Fig. 7 cooperates with the protector finger 162 to provide a narrow opening between the extremities of these two parts through which the filling may easily escape, but cannot reenter.

A new and useful form of binder-guide has been developed, comprising the right-angled extensions 140 and 142, Figs. 7 and 8, forming part with the front wall of the shifting shuttle-box, and being joined also to the fin 91.

Fig. 12 shows diagrammatically the method or 45 system of operation of my invention. It portrays the complete cycle of replenishment for each of the three shuttles, presuming all three to have reached substantial exhaustion in sequence. In the replenishing cycle for shuttle #1, at stage 50 #1, this shuttle has just been picked across to the left-hand top cell and lifted to bring its contents into engagement with the feeler, but this motion of the left-hand boxes, and full feeling contact, had not been completed until the lay 55 had passed front center.

The boxes are arranged to shift at one end of the lay only during each rotation of the crank-shaft, hence the left-hand boxes stay elevated for almost two complete turns of the crankshaft, and thus the feeler remains in feeling contact for this full period, its striker engaging the finger 15 and setting the latch 27 as the lay beats up in the middle of this period, which engagement comes between the events pictured in stages #1 65 and #2. Following the shift of shuttle #1 into feeling position, shuttle #2 is picked out from under and across the loom, as indicated in stage #1. Then the right-hand box is dropped, and shuttle #3 is picked out of the top or replenishing 70 cell of the right-hand box and into the left-

hand cell just vacated by shuttle #2, as shown in stage #2. The left-hand box having been dropped, shuttle #1 is picked across to the replenishing cell of the right-hand box as indicated in stage #3. Thereafter the right-hand box 75 rises, and shuttle #2 is picked out from under the replenishing cell, as indicated in stage #4. Then, as the lay arrives at front center, the transfer of a new bobbin into shuttle #1 occupying the lifted replenishing cell of the right-hand box is 10 effected by the replenishing mechanism described, the actuator 33 having shortly previously made engagement with and thrust forward the latch 27 to present the transerrer-dog 63 to the blow of the lay as it completes this forward stroke. 15 The transfer being completed while the lay is forward, it is finished long before shuttle #3 arrives beneath shuttle #1, which occurs at bottom center or the completion of the following pick. From this it will be plain that the complete 20 replenishing cycle, from the time of detection of approaching exhaustion to replenishment of this spent filling-carrier, takes four cycles of the loom, or four turns of the crankshaft.

An exactly similar replenishing cycle occurs 25 for shuttles #2 and #3, as indicated by the numerals and positions on the diagram of Fig. 12.

Though the invention has been presented as embodied in a loom having four shuttle cells, two to each shifting shuttle-box at each end of the 30 lay, and employing three shuttles, it is obvious that any desired number of shuttles may be used in mixing the filling, the only requirement being that the shuttle-box at the replenishing end 35 shall have only one shuttle in it at the moment of transfer.

Fig. 20 shows an alternative method of employing the basic principle of the invention of employing an empty cell of the change-box as a corridor for the exchange of bobbins. In this 40 case, it is the top cell 164 of the change-box which is empty, the shuttle 166 containing the spent filling-carrier 168 occupying the bottom cell 170. The transerrer 172 is arranged for a longer stroke and for penetrating through the empty 45 cell to reach the shuttle in the cell below; it is equipped with spring clips 174 grasping the new bobbin, or other suitable means to control the new bobbin in its increased travel from the hopper to the shuttle. The arrangement of all other 50 cooperating parts may be as described hereinbefore, or as preferred, and need not be described again.

As is obvious, the invention principles may be applied wherever replenishment is to be effected 55 in a shuttle occupying a shifting shuttle-box, and even when there is a plain box at the other end of the lay, as in the case of a 2x1 loom, in order to simplify the filling-feeler arrangements.

While I have illustrated and described certain 60 forms in which the invention may be embodied, I am aware that many modifications may be made therein by any person skilled in the art, without departing from the scope of the invention as expressed in the claims. Therefore, I do not 65 wish to be limited to the particular forms shown, or to the details of construction thereof, but

What I do claim is:—

1. In a drop-box loom, in combination, box-motion devices yieldingly connected to the drop-box, means positively maintaining a drop-box at rest with respect to the lay while the latter is at and about front center, and devices automatically inserting a fresh filling-supply into a shuttle occupying such box from above during the 75

- period while the box is held against movement with respect to the lay by such positive means.
2. In a drop-box loom, in combination, a drop box having two adjacent cells, shuttles, filling-carriers carried thereby, a filling-feeler, means to eject from a shuttle occupying a cell in the drop-box, a filling-carrier found to be substantially depleted by the feeler, and means operating to withdraw the binder of an adjacent cell to permit passage through the latter of the ejected filling-carrier.
3. In a drop-box loom, in combination, box-motion devices connected to the drop-box through a give-way, automatic filling replenishing devices cooperating with a shuttle occupying a cell in the drop-box, and means for positively locking the drop-box against movement relatively to the lay at the moment of replenishment.
4. In a loom, in combination, a lay, a shuttle thereon, means automatically inserting a fresh filling bobbin in the shuttle, a self-threading device in connection with the shuttle to be threaded by the drawing-off of filling from within the shuttle, and means operating to draw the filling 25 axially off from the bobbin as the lay recedes and thus to thread the self-threading device before the replenished shuttle is picked.
5. In a shifting shuttle-box loom, automatic filling-replenishing devices including a transfer-30 rer inserting a fresh bobbin in a shuttle on the lay, an actuator making a working stroke once in every four cycles of the loom, and a feeler determining the transmission of an actuating impulse from the actuator to the transferrer.
6. In a loom, in combination, automatic filling-replenishing devices, including bobbin-feeding means, a stop to locate the bobbins successively in transfer position as they are fed, a shuttle-feeler, actuating means therefor, and means to actuate the bobbin-feeding means from the shuttle-feeler while the shuttle-feeler is moving into feeling position to bring the bobbin next to be transferred into contact with the stop and hence accurately in transfer position.
7. In a loom, in combination, a lay, automatic filling-replenishing mechanism, an actuator setting the replenishing mechanism in readiness for operation by the lay, a cam rendering the actuator inoperative for three loom cycles and rendering it operative on the fourth cycle, and a filling-feeler establishing operative connection between the actuator and the replenishing mechanism.
8. In a loom, in combination, automatic filling-replenishing mechanism, a shuttle having a self-threading device, and means maintaining the new 25 filling-end extending outwardly over and beyond the self-threading device in the plane of the shuttle axis as the lay recedes following a replenishing action.
